UNITED STATES PATENT OFFICE.

MERRICK A. MIHILLS, OF CHICAGO, ILLINOIS.

RAZOR-STROP.

950,451.

Specification of Letters Patent. Patented Feb. 22, 1910.

Application filed June 29, 1909. Serial No. 505,024.

To all whom it may concern:

Be it known that I, MERRICK A. MIHILLS, a citizen of the United States, residing at Chicago, in the county of Cook and State of Illinois, have invented new and useful Improvements in Razor-Strops, of which the following is a specification.

The purpose of the present invention is to devise a strop for providing razors and other like implements with keen cutting edges, the invention supplying a strop which will both whet and strop the razor at one and the same operation.

The invention contemplates a strop having sharpening or abrading material embedded in the surface thereof and having smooth and roughened portions acting jointly both for cleaning the edge and rendering the same keen for effective service in shaving.

The invention consists of the novel features, details of construction and combinations of parts which hereinafter will be more particularly set forth, illustrated in the accompanying drawings and pointed out in the appended claims.

Referring to the drawings forming a part of the specification: Figure 1 is a front view of a razor strop embodying the invention, an intermediate portion being broken away. Fig. 2 is a view of the strop as seen from the reverse side, an end portion being broken away. Fig. 3 is a transverse section on the line 3—3 of Fig. 1 showing the strop on a larger scale.

Corresponding and like parts are referred to in the following description and indicated in all the views of the drawings by the same reference characters.

The strop may be constructed of any suitable material commonly employed in the manufacture of such devices and may comprise a number of plies or consist of a single piece. When the strop is constructed of a plurality of plies or layers, one surface may be of leather and the other of canvas or like textile.

In accordance with this invention, a series of pockets or depressions 1 are formed in one side of the strop and receive a sharpening or abrasive material such as carborundum, emery, pulverized whet stone or the like, said material being combined with paraffin or other oleaginous material forming a binder or vehicle so as to retain the pulverulent particles together and retain the

same in place in the pockets or depressions of the strop. The pockets or depressions 1 are comparatively small and may be formed in any manner so as to receive a small quantity of the abrading material. The pockets may be filled with the material in any manner and such material compressed or forced into the pockets by being rolled therein or subjected to compressive force in any manner. The pockets filled with the abrasive or sharpening material constitute in effect spots and are so related as to form a strip in the length of the strop and are spaced to provide intermediate smooth surfaces 70 which act upon the edge of the razor or other keen-edged implement for sharpening the same and imparting a smoothness and keenness to the edge during the stropping operation.

A series of grooves and fine ribs 2 are provided adjacent the strip containing spots of sharpening material and these grooves and ribs likewise form a strip, the grooves and ribs being exceedingly fine and arranged transversely or at a right angle to the length of the strop whereby in the operation of stropping, a razor, the blade is drawn over the grooves and ribs at an oblique angle thereto thereby producing the best effect in the provision of a keen edge. The fine grooves and ribs 2 may be formed in any manner. In the preferable construction, the strip containing the spots of abrading material is located midway between the longitudinal edges of the strop and the strips or edge portions upon opposite sides of the intermediate strip are provided with fine ribs and grooves.

A strop constructed in the manner herein disclosed performs the dual function of both whetting and stropping at one and the same time thereby greatly facilitating the operation and insuring the provision of a keen edge with less effort and preventing fatigue. After the razor or other keen-edged implement has been stropped upon the side of the strop provided with the strips of abrasive material and toothed portions the strop is reversed and the edge made finer by stropping the razor upon the smooth side 3 of the strop as indicated in Fig. 2.

From the foregoing description, taken in connection with the accompanying drawings, the advantages of the construction and of the method of operation will be readily apparent to those skilled in the art

to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

10 Having thus described the invention, what is claimed is—

1. A strop having a portion of its surface provided with spots of abrasive material and having smooth surfaced portions between the spots and having another portion 15 provided with fine ribs and grooves.

2. A strop having a surface formed in parallel strips, one strip comprising fine grooves and ribs and the other strip having spots of abrasive material embedded therein. 20

3. A strop having an intermediate portion between its longitudinal edges provided with spots of abrasive material embedded therein and having the edge portions at the sides of the intermediate portion formed 25 with fine grooves and ribs.

In testimony whereof I affix my signature in presence of two witnesses.

MERRICK A. MIHILLS.
